(57) **CLAIM**

The ornamental design for an upright electronic gaming machine, as shown and described, except as disclaimed herein.

DESCRIPTION

FIG. 1 is a perspective view of the upright electronic gaming machine.

FIG. 2 is a front elevational view thereof.

FIG. 3 is a side elevational view thereof; and,

FIG. 4 is a top plan view thereof. The broken lines in FIG. 4 are included for the purpose of illustrating a portion of the rear that forms no part of the claimed design.

The bottom and rear views of the machine illustrated in FIGS. 1-4 are hereby disclaimed and form no part of the claimed design.

1 Claim, 4 Drawing Sheets

FIG. 1

FIG. 2

FIG. 3

FIG. 4
